F. C. RUTZ

BRAKE DEVICE FOR RAILWAY CARS

Filed May 5, 1926

Patented Aug. 23, 1927.

1,639,669

UNITED STATES PATENT OFFICE.

FRANK C. RUTZ, OF ROCKFORD, ILLINOIS

BRAKE DEVICE FOR RAILWAY CARS.

Application filed May 5, 1926. Serial No. 106,790.

This invention relates to brake devices for railway cars and is an improvement on the invention described in my U. S. Letters Patent No. 1,624,510, granted April 12, 1927.

In said patent I have explained some of the reasons why it is desired to improve the present so-called standard hand wheel or lever brake with the view to increasing or boosting the braking force so that it will be at least equal to, if not greater than, that applied by the air brake mechanism. That invention is characterized by the provision of a mast drum mounted for rotation in a casing and having a spiral groove of approximately uniform pitch and diameter in which a cable or other suitable flexible means connected with the brake rigging is adapted to be wound for exerting the braking pull, and in the further provision that the mast drum is so shaped as to enable the center line of the pull to be brought close to its center to secure a shorted lever arm and consequently, a greater mechanical advantage. As a result a smooth, constant and increased effective braking force is obtained by the application of the normal hand braking force. Said invention further provides against fouling of the cable or flexible means on the mast drum when winding or unwinding.

The primary object of the present invention is to attain a similar result under the same or similar conditions with the use of the standard link chain now employed with brake devices in general, in place of the cable shown in my prior application. By the use of a chain of this kind the conventions of railway practice are adhered to and, at the same time, a new result is accomplished in hand brakes with the use of a chain and drum, in that the desired increase in effective braking force is obtained to meet the railway requirements that the braking force against the wheels be equal approximately to 60% of the light weight of the car. This result is obtained in the present invention by the provision of a mast drum having a spiral thread for receiving the standard chain, the pitch of the thread being preferably uniform from end to end of the drum and the thread and groove being so shaped as to insure a constant lever arm with the alternate links approximately meeting the longitudinal axis of the drum. While the present invention is predicated primarily on this type of mast

drum for a brake chain, I prefer that it shall be employed substantially in the combination disclosed in my prior application in which the mast drum is mounted for rotation in a housing or casing adapted to be in turn mounted on the railway car in place of the usual strap which provides support for the lower end of the brake shaft. This gives a simple and thoroughly practical construction which may be economically produced.

Other objects and attendant advantages will be appreciated by those skilled in this art as the invention becomes better understood by reference to the following description when considered in connection with the accompanying drawings, in which—

Figure 1, is a fragmentary side elevation of one end of a railway car equipped with a hand brake device embodying my invention;

Fig. 2, is an enlarged vertical section through the brake device showing the mast drum in elevation;

Fig. 3, is a horizontal section taken substantially on the line 3—3 of Fig. 2;

Fig. 4, is a further enlarged fragmentary section taken substantially on the line designated by 4, Fig. 3, this section extending only to the longitudinal center referred to hereinafter; and

Fig. 5 is a similar fragmentary section showing a modified form of groove or chain score in the mast drum.

While my invention is primarily intended for application in a hand brake device it should be understood that in its broader sense it is applicable to any railway brake whether operated by hand or otherwise. The present illustration is, therefore, merely a preferred embodiment and is to some degree diagrammatic, especially in respect to the connection between the brake chain and brake rigging.

The drawing shows one end of a conventional freight box car the body of which is designated generally by 5. Only such parts of the brake mechanism are shown as are necessary for an understanding of the present invention. The well known parts comprise a brake shaft or mast 6, an upper bearing bracket 7, a wheel 8 fixed to the top end of the shaft, a ratchet wheel 9 fixed to the shaft and having the usual pawl for preventing the wheel and shaft from turning backward, and a brake rod 11 connected through the brake rigging and the cylinder push rod

and the brake shoes in a suitable or preferred manner well known in this art.

In applying my invention to a railway car having the usual hand brake, I remove the 5 brake shaft 6, cut off the cylindrical drum at the lower end thereof, square the end 12 of the shaft and substitute for the cut off end a mast drum designated generally by 13 which has a squared socket 14 for the reception 19 of the squared end 13 of the brake shaft. The mast drum and brake shaft may be secured together by any suitable means such, for example, as a bolt 15 passing through the interfitting parts.

15 The mast drum is supported for rotation in a casing or housing designated generally by 16 which in turn is shaped for rigid attachment to the railway car. This casing replaces the usual mast step which gives support to the lower end of the usual brake shaft. The casing may have a broad flat portion 17 adapted to be clamped against the car structure or body by bolts 18, and a horizontal rib 19 adapted to seat against the underside of the car body for locating the casing and for resisting any tendencies to tilt the same. The casing is further shaped to provide a cylindrical portion 21 depending from the attaching portion and being open 23 at its top for reception of the mast drum and having a bottom wall 22 providing a bearing 23 for the reduced lower end 24 of the mast drum. The mast drum is held from upward displacement by suitable 35 means such as a cotter pin 25 passing through its projecting lower end 24. The casing further provides lateral bearing support for the upper end of the mast drum, this purpose being served by a semi-circular bearing surface 26 for the cylindrical portion 27 of the drum which is located intermediate the square socket end or shank and the spirally grooved portion of the mast drum. It will be observed that the cylindrical portion 27 also serves to substantially 45 close the opening at the upper end of the cylindrical portion 21 of the casing.

The mast drum is spirally grooved substantially from end to end in a novel manner to provide for the winding of a standard 50 brake chain with the chain approximately meeting on successive convolutions the longitudinal center or axis. The mast drum is further designed to insure proper and positive winding of the chain in the spiral groove and to prevent slippage and displacement of the links from such determined arrangement on the drum. The mast drum is also designed so as to provide a cross-section 60 adequate to take care of the heavy strains and stresses incidental to the varying conditions of usage.

As shown in Fig. 4 the cross-section of the 65 spiral teeth is substantially T-shape, identified by the parts 28 and 29, the latter of

which provide continuous shoulders on which the alternate links 31 disposed parallel with the axis 32 are adapted to ride and the intermediate leg part 28 providing a continuous outstanding tooth which defines 70 the pitch and space into which the chain is adapted to enter and leave the drum. The space or groove between the spiral teeth is continued inwardly between adjoining shoulder parts 29 to provide a groove or score 33 reaching approximately to the axis 32. This portion of the spiral groove or chain score is for receiving the alternate links 34 intermediate the links 31 and is disposed at substantially right angles thereto in a plane transverse to the said axis. The total depth of the chain score or groove is, therefore, equal to, and preferably slightly greater than, the outside width or dimension 80 of the chain as shown clearly in Figs. 3 and 4. The cylindrical casing 21 embraces the spiral portion of the drum so as to form an effective enclosing wall thereabout leaving an opening 35 from end to end through which the chain passes. As shown in Fig. 3 this opening is disposed tangential to the mast drum and the edges are flanked by reinforcing flanges 36. The enclosing wall formed by the casing serves, therefore, to guide the chain in its passage to and from the mast drum and to prevent displacement of the chain therefrom.

One end 37 of the chain is suitably fastened to the mast drum as, for example, by means of a bolt 38 passing through this terminal link and threaded into the drum proper. This end of the mast drum is recessed at 39 for the reception of the link 37 and a bolt hole is drilled from the upper end of the drum through the body at both 100 sides of the recess 39 so as to provide for rigid and substantial attachment of the bolt to the drum. The opposite end of the chain after having been passed through a pulley 41 on the brake rod 11 is attached at 42 to the center body sill or to any suitable point on the car. The connection between the chain, brake rigging and car may, however, be varied according to the conditions at hand or to meet any particular requirements; consequently, the present construction is merely for purpose of illustration.

In practice, to tighten the brakes the brake shaft will be turned so as to rotate the mast drum in a clock-wise direction viewing Fig. 120 3, thus winding the chain in the spiral groove upon said drum. Because of the shape of the mast drum the chain will properly follow the spiral groove, each alternate link 34 riding in the deepest portion or score 125 33 of the groove and each alternate link 31 riding on the shoulders 29 between the outstanding tooth parts 28. By reason of the fact that the chain is brought to the axis the effective lever arm is shorter than has 130

heretofore been attained as a constant with the use of a standard chain wound on a mast drum. In other words, throughout the successive convolutions of the chain-receiving groove the chain approximately meets and, in fact, it does meet in practice, as shown on Figs. 4 and 5 of the present drawings, the axis of the drum. As a result the effective lever arm is constant at all times regardless of the particular position or stage of the winding. This is particularly desirable in that it enables the maximum braking force to be applied irrespective of variations in the length of the chain or in the particular point on the drum at which the brakes are brought home with the maximum pull. The fact that this point is a variable is taken care of excellently with the present construction. It should also be noted that since the greatest lateral stress on the drum occurs at a time when the chain is approximately midway between its ends there is apt to be a slight lateral deflection of the drum toward the side of the pull. To prevent injurious deflection and to resist this side thrust the wall 43 of the casing is carried close to the periphery of the drum and acts as a thrust bearing or wall. The tendency to spring this wall is resisted by a series of circumferential reenforcing ribs 44.

In Fig. 5, I have shown a modified form of mast drum in which the spiral groove or chain score 45 does not have the shoulders 29 above-mentioned, but instead the bottom of the groove is shaped to receive the links of the chain in any angular relation thereof. In other respects, however, this form of the mast drum is the same as the embodiment first above described. The present embodiment is, however, advanta-

geous in that it lends itself better to casting the mast drum to the desired shape in one piece.

With the use of my improvements a comparatively smooth steady braking pull may be applied with a constant leverage, the effective leverage being such that the average hand force applied on the hand wheel or lever is capable of applying a braking force equal to that applied by an air brake of standard increased requirements. This result has not, prior to my invention, been accomplished, so far as I am aware, with the use of a conventional standard chain wound on a mast drum or the equivalent. It is believed, therefore, that the use of a chain and mast drum as claimed herein is new and that in practice it may be applied with modification to brake devices of the character described, without departing from the spirit and scope of the invention as expressed in the appended claim, in which—

I claim:

A hand operated brake device of the character described, comprising a rotatable mast drum having a spiral groove, a brake chain wound in said groove on the mast drum, the bottom of the groove from end to end being approximately coincident with the axis of the drum, the drum having a bearing member at each end, and a casing enclosing the spiral portion of the drum and providing a bearing for each bearing member thereof and having an elongated chain opening between said bearings through which the chain emanates.

In witness of the foregoing I affix my signature.

FRANK C. RUTZ.
